UNITED STATES PATENT OFFICE

IRVING BROMILEY, OF NEW ROCHELLE, NEW YORK, ASSIGNOR TO CLIQUOT CLUB COMPANY, OF MILLIS, MASSACHUSETTS, A CORPORATION OF MASSACHUSETTS

DESIGN FOR A BOTTLE

Application filed October 1, 1928. Serial No. 28,331. Term of patent 14 years.

To all whom it may concern:

Be it known that I, IRVING BROMILEY, a citizen of the United States, residing at New Rochelle, in the county of Westchester, State of New York, have invented a new, original, and ornamental Design for Bottle, of which the following is a specification, reference being had to the accompanying drawing, forming part thereof.

The figure is a side elevation of a bottle showing my new design.

The bottle embodying the design is of cylindrical form at the portion extending upward from the base for a distance equal to approximately one-third of the entire height of the bottle; thence for a portion equal to approximately one-half of the height of the

bottle the contour is slightly convex, merging into the cylindrical base portion with a somewhat more pronounced convexity; while the upper portion or neck of the bottle is lightly concave; and the neck terminates in a swelling of spheroidal form surmounted by a lip, also of spheroidal form but of less width, these spheroidal portions being separated by pronounced groove.

The portion of the bottle between the cylindrical portion and the spheroidal enlargements mentioned is accordingly of the nature of a flat ogee curve.

I claim:

The ornamental design for a bottle as shown and described.

IRVING BROMILEY.
